DESIGN FOR A TOY

Peter V. Chicone and Patrick Ciccone,
St. Paul, Minn.

Application October 23, 1944, Serial No. 115,928

Term of patent 3½ years

(Cl. D34—15)

To all whom it may concern:

Be it known that we, Peter V. Chicone and Patrick Ciccone, both citizens of the United States, residing at St. Paul in the county of Ramsey and State of Minnesota, have invented a new, original, and ornamental Design for a Toy, of which the following is a specification, reference being had to the accompanying drawing, forming a part thereof.

We claim:

The ornamental design for a toy, as shown.

PETER V. CHICONE.
PATRICK CICcone.
